UNITED STATES PATENT OFFICE.

JACOB KRONHEIM, OF CLEVELAND, OHIO.

RESILIENT BOTTOM FOR COUCHES, CHAIRS, ETC.

Application filed June 9, 1928. Serial No. 284,029.

My invention relates to resilient bottoms for couches, chairs, box springs, and like articles of manufacture. In general my object is to provide a durable bottom of exceptional 5 resiliency and low cost, which will greatly simplify the steps usually taken in manufacturing and upholstering articles such as herein mentioned. In that connection reference may be had to my Letters Patent No. 10 1,664,934, dated April 3, 1928, for a chair or couch, the present invention being an improvement in part thereover, all as herein-after shown and described and more concisely set forth in the claims.

15 Referring first to the accompanying drawings, Fig. 1 is a top view, on a reduced scale, of a resilient bottom constructed according to my invention. Fig. 2 is a vertical section, on a slightly larger scale, of the bottom attached to a wooden frame, such as a couch or chair frame. Fig. 3 is a bottom view of the bottom, partly broken away in places, stretched within a rectangular frame. Fig. 20 4 is a perspective view of one corner of the bottom, and Fig. 5 a sectional view thereof, showing the mode and manner of connecting and seating the main springs.

In constructing a chair, davenport couch, or box spring, the general practice is to build 30 a suitable frame first, then install a spring bottom in the frame, and finally cover or encase the assembled parts with textile fabrics. In order to simplify operations of that kind, I provide a bottom —A— which is constructed and assembled as a separate unit in 35 the shop, and which may be manufactured and sold as a separate article, and readily installed by any manufacturer of furniture in frames of standard sizes.

40 This bottom —A— is a composite structure built as follows:

A sheet of strong canvas, duck, or other closely woven material 2 is hemmed to enclose a wire frame 3 of somewhat smaller size than the opening in the frame B within which it 45 is to be installed. Separate strips 4 of cloth of lighter weight than the canvas are sewed to the bottom face of sheet 2 parallel with three sides thereof and contiguous to hem 5 containing wire 3. These border strips provide loose flaps which are tacked to the wooden frame B eventually. A large piece 6 of loosely-woven cloth, such as heavy burlap is sewed to the top of canvas piece 2, and these pieces are stretched tightly in facia 55 contact within wire frame 3. A series of coiled wire springs 7 of hour glass shape, or any other form, are seated upright in spaced relation in rows between the sides of wire frame 3, with the circular bottom loop 8 of 60 each spring seated partly upon canvas piece 2 and partly upon the burlap covering piece 6. Thus each bottom loop 8 is in the form of a coil with the extremity 9 of the wire detached, or free from the body of the coil so 65 that this extremity may be caused to penetrate and pass through the loosely woven body or meshes of the top burlap piece 6 when the spring is seated thereon and rotated by hand during the assembling or building opera 70 tions of the bottom. In that proceeding the sharp end 9 of the wire is threaded in and out of the burlap several times so that the bottom loop or coil 8 is interfretted and interlocked with the burlap at several places 75 radially of the spring, thereby anchoring and fastening the spring in a very simple and quick way to the fabric base.

Each spring is thereby prevented from shifting horizontally from its selected position or seat upon the canvas, and the spring is also held down in place upon the canvas and cannot be easily disconnected or displaced when raised or lifted. The assembling of the springs in spaced relation and in a group 80 85 is greatly expedited by using springs with free ends coiled and interlocked with the burlap as described, and the use of an open mesh fabric upon the top of a closely-woven material promotes easy attachment and a firm 90 seating for the springs.

Having the required number of springs attached to the flexible base as described, the upper ends of the springs are connected together, in any suitable way. For example, 95 the springs may be connected together by twine and each spring placed under a certain degree of compression by attaching the twine to wire frame 3. The tied spring structure may now be readily installed within an open 100 wooden or metal frame B by connecting the wire frame 3 and the border edges of the fabric to the four sides thereof. Preferably three sides of the wire frame are connected by closely coiled tension springs 10 to three 105 metal strips 11 which may be screwed or nailed to three sides of the main frame B, while the fourth side or front border edge

of wire frame 3 is connected to the front rail 12 of frame B by short and relatively stiff springs 14 comprising a single coil made of wire having straight connecting portions terminating in looped or hooked ends 15.

After the bottom is attached to the four sides of the main frame by the separate sets of tension springs 10 and 14, respectively, the border flanges 4 are extended downwardly 10 at an inclination and tacked to the bottom edges of the side members of main frame B, thereby closing the space at three sides of the resilient bottom. Tension springs 10 and 14 are of sufficient number and strength to 15 stretch the flexible bottom A tightly within frame B, and they cooperate with the compression springs 7 in yieldingly supporting the load. The movement of bottom A downwardly under the load is greatest where 20 the load is applied locally but nevertheless the load is in part distributed to all of the supporting springs, and the border flaps 4 are free to flex without strain where fastened to the respective frames when bottom 25 A is under load.

In completing the installation a suitable covering encases or is stretched over the springs carried by bottom A and in a couch or chair it is also customary to place 30 a seat or cushion thereon, as indicated in dotted lines in Fig. 2. However, bottom A with its complement of seating and supporting springs, may be manufactured and sold as a complete unit to manufacturers 35 of furniture and similar household goods, and installed by them in frames of any suitable character or kind, and the appended claims therefore are not to be construed as limiting the use of the invention solely to the 40 articles specifically enumerated herein:

What I claim, is:

1. A resilient bottom for couches, chairs, etc., comprising a flexible base member and a fabric covering for said member and in facial contact therewith, together with coiled 45 springs, seated upon said base member and having seating portions interlocked with said covering.

2. A resilient bottom for couches, chairs, 50 etc., comprising superposed layers of woven materials, and a series of coiled wire springs

seated upon said layers and interfretted with the upper layers of said woven materials.

3. A resilient bottom for couches, chairs, etc., comprising a base member of woven fabric, and a wire frame therefor, a covering of woven fabric affixed to the top of said base member in facial contact therewith, and coiled wire springs seated upon said base member and interlocked with said covering. 55

4. In couches, chairs, etc., including a frame structure, a resilient bottom unit comprising a wire frame, a base sheet of closely woven fabric stretched within said frame, flaps at the sides of the said frame adapted to be attached to the bottom rail of said frame structure, springs seated upon said sheet of fabric, covering means for said base sheet, securing the seating portions of said springs to said sheet, and helical springs connected to the 60 border edges of said base sheet and to said wire frame for connection of said resilient bottom unit to said frame structure. 70

5. A resilient bottom unit for couches, chairs, etc., comprising a flexible base sheet, 75 reinforcing means at the border edges of said sheet, a series of coiled springs seated upon said sheet, and means extending over the top of said sheet and in facial contact therewith for holding the seating portions of said 80 springs in situ.

6. A resilient bottom unit for couches, chairs, etc., comprising a rectangular flexible base member, coiled wire springs seated upon and fastened to said base member, a series of 85 helical wire springs connected to the rear and end edges of said base member, and a series of short stiffer springs connected to the front side of said member.

7. A resilient bottom for couches, chairs, 90 etc., comprising a flexible base member having a top covering of loosely woven material in facial contact affixed thereto, coiled springs having base loops terminating in free ends interlocked with said loosely woven material 95 while seated upon said base member, and means at all border edges of said base member for suspending said assembly of parts yieldingly within an open frame.

In testimony whereof I affix my signature. 100

JACOB KRONHEIM
